UNITED STATES PATENT OFFICE.

WILLIAM K. LIGGETT, OF COLUMBUS, OHIO, ASSIGNOR TO THE JEFFREY MANUFACTURING COMPANY, OF COLUMBUS, OHIO, A CORPORATION OF OHIO.

SHOVELING AND LOADING APPARATUS.

1,293,132.

Spécification of Letters Patent.

Patented Feb. 4, 1919.

Application filed September 18, 1912. Serial No. 721,025.

To all whom it may concern:

Be it known that I, WILLIAM K. LIGGETT, a citizen of the United States, residing at Columbus, in the county of Franklin and 5 State of Ohio, have invented certain new and useful Improvements in Shoveling and Loading Apparatus, of which the following is a specification, reference being had therein to the accompanying drawings.

10 This invention relates to an improved shoveling and loading apparatus. It is particularly designed for the shoveling or picking up, elevating and delivering of coal or other materials from piles on the ground or 15 floor surfaces.

The object is to provide a simplified, light, but strong and durable, structure for this purpose, one which can be readily moved from place to place, easily brought to its 20 work, and manipulated with readiness while being operated.

Figure 1 is a plan view of a machine embodying my invention.

Fig. 2 is a sectional elevation, taken along 25 the line 2—2 of Fig. 1.

Fig. 3 is a sectional view taken along the line 3—3 of Fig. 2.

Fig. 4 is a detail view of a section of the conveyer.

30 Fig. 5 is an end view.

Fig. 6 is a diagrammatic plan view showing one way in which the machine can be used.

In the drawings the apparatus is shown 35 as comprising a main frame, supporting wheels, an inclined frame, a shovel frame with a shovel plate rigidly secured to the inclined frame, an endless conveyer, means for propelling the machine bodily over the 40 ground, means for either lifting the front end, more or less, or causing it to move sideways one way or the other, and a motor or engine on the main frame connected to the conveyer.

45 The main frame is indicated as a whole by A. It may be constructed of any suitable parts. As shown, it has side sills (1) and cross bars (2) and (3).

This frame is carried at the rear by a 50 wheel support, there being two supporting ground wheels B, one on each side of the central longitudinal, vertical plane of the

machine, and these are arranged to give it firm support and prevent it from being displaced laterally. Preferably they are in 55 axial alinement, that is, mounted upon one and the same axis. But there can be variations in this respect. They are not track wheels but preferably have wide tires and peripheral surfaces whereby they can rest 60 directly upon the ground and can travel freely in any direction, without tracks.

Upon this frame and its wheels is arranged an inclined frame C, which extends from points at the ground plane, in front 65 of the wheels B, on lines extending backward and upward above the wheels to points behind them. This frame can be constructed in any suitable way; for example, with main side sill bars (5) and suitable cross bars 70 (6). There should be braces (4) such as shown extending from the main frame to and fastened at, points near the rear upper end of the inclined frame. On the bars (5) and (6) there are arranged sheet metal 75 plates 7 having material-supporting parts (8) which are extended horizontally, and inclined side walls (9). By preference there are two of these sheet plates shaped as described, one at each side of the inclined 80 frame. The conveyer, to be described, travels in the trough-like space formed by the parts (8) and (9) and the sill bars (5). At the center of this part of the structure there is a connecting and covering plate (11) 85 formed of sheet metal and arranged in the way illustrated so as to form a tight box which will retain the material and prevent it from falling down between the two strands of the conveyer.

90 At the lower end the shoveling element of the apparatus is arranged, as at D. This comprises the shovel plate (12) and a carrying and supporting frame (13), both being rigidly secured to the lower front end of 95 the inclined frame C.

The shovel plate is preferably flat and is arranged to have its lower surface lie normally in the horizontal plane of the ground line, that is the plane where the lowermost points of the wheels B contact with the ground or general underlying support. Frame bars (14) give the shovel element firm support, these being rigidly connected 100

to the shovel plate and to the bars of the uprising or inclined frame. The frame of the shovel element has also an upper or top plate (15) secured to the bars (14).

5 E indicates a conveying device by which the material that lies on the shovel plate D is first taken backward therefrom and then carried up to the inclined frame C to the points of delivery. It is an endless conveyer, preferably formed of chain-links to which are secured flights or scrapers. The chain is built up in sections, or sets of links, as at (16) (17) (18), which links are of the ordinary oval shape. Each set is connected to the next by a scraper link (19), this being a casting with hooks (20) and a laterally extending flight (21) cast integral therewith.

At (22) there is a driving sprocket wheel 20 arranged in the planes of travel of the conveyer E, and receiving power from any suitable source. As shown, the shaft (24) of this wheel is provided with a worm wheel (25) with which meshes worm (26) on a shaft (27) carrying a pulley (28). Preferably there is a motor, electric or otherwise, which is designated in the drawings at 41. The belt 40 connects the motor with the pulley 28.

30 On the shovel element there is mounted the guide or idler sprocket wheel (29), it being supported by a pin or bolt (30) carried by the shovel frame. It is so arranged that the chain and flights (21) move horizontally along the upper surface of the shovel plate (12). At (31) there is a vertically arranged idler wheel or guide wheel for the inactive or down-moving part of the conveyer, and at (32) another similar wheel 35 for the upgoing or active part. These wheels are mounted with their axis near the apex of the angle between the rigidly connected shovel plate or frame and the inclined frame.

The endless chain as it passes the idler 45 wheels at (31) (32) is deflected from one line of travel to another line and yet the flights turn in the same horizontal planes as the chains.

The diameters of the sprocket wheels (22) 50 and (29) are such that the lines of the chain lie close in to the vertical parts (5) of guideway (7). The flights (21) extend horizontally outward with their lower edges arranged to travel in contact with the horizontal part 8 of the guideway and also travel 55 across the upper surface of the shovel plate 12.

The top plate 15 on the shovel element 60 serves as a guard to prevent the chain links from moving upward while they are traveling around sprocket wheel (29).

The shovel element is adapted to have a 65 lever-like device attached therewith such as shown at (33). At 34, 34 there are loops attached to the shovel, or a socket can be here

used which is capable of having a lever situated therein and withdrawn therefrom.

This lever has a number of purposes. The operative can grasp it and cause it to exert more or less of a lifting action at the front 70 end of the apparatus; and this can be done when the machine is to be propelled forward, or backward for some distance or to pass by obstacles. It can be used for exerting force laterally upon the shovel to 75 cause it to move under the material that is to be shoveled and lifted.

The parts of the apparatus are so related that when in operation the center of gravity 80 of the apparatus and of the load is well in front of the transverse vertical plane of the wheel axis; and consequently the machine is held firmly in position on the ground and prevented from tipping backward.

But at the same time the design is such 85 that the excess of load at the front is not so great as to prevent an operative from lifting the front end, or shovel end, up, to throw the weight more upon the ground wheels thus permitting free and speedy movement 90 of the entire apparatus to adjust it for new work or, work at a new position.

When the machine is free of any load the center of gravity is nearer the aforesaid vertical plane of the wheel axis and it can then 95 be readily turned around with the wheels in any direction, or can as readily be taken backward bodily or forward.

By having the frame work mounted upon two wheels and held throughout, in rigid 100 relation thereto, bodily movements of the entire apparatus can be speedily accomplished.

This is in strong contrast to the machines in which a wheel frame or track frame and the inclined elevator frame are connected together flexibly or by hinges or pivots, as in such case the weight at the forward end of the apparatus is relatively greatly increased.

I employ also a power device for causing the bodily movement of the mechanism. 110 As shown it consists of a cable or chain (35) having a hook or equivalent for attaching it to some external anchor.

The rope or chain passes across the plane 115 of the conveying apparatus to the under side thereof and is connected to a winder. This consists, as shown, of the drum 36, to which power is applied from a manual motor, such as a crank shaft (37) connected by gearing to the drum. The rope passes from the drum on the under side of the conveyer to the forward side on lines which are between the inactive part and the active part 120 of the conveyer and hence there is no interference with the moving parts of the machine from this cable or chain.

In order to swing the apparatus around on the wheels as a pivotal support, that is, 125 in order to make the front part move laterally and thrust the shovel under the coal, or 130

other material, guides (38) are provided just in front of the conveyer in the form of sheaves or guide wheels, which hold the cable or chain in position, though permitting 5 the front part of it to be deflected to the right or left.

Although I have above referred to one side or leg of the conveyer as being the down-going or inactive side and to the other as the 10 up-going or active part, it is to be understood that the machine is reversible as concerns its movement laterally. That is to say, the rigid flat stationary shovel plate (12) projects toward the right and also toward 15 the left from its central longitudinal line far enough to permit it to be forced under a mass of material on either side. The conveyer is reversible. The flights or plates (21) are adapted for operation when traveling 20 in either direction. The power actuated moving device (35) is provided with a hook or fastener (35') which, can be secured to an anchor post or equivalent stationary device either on the right side of the machine 25 or on the left side, according to circumstances.

The manner of using the shoveling and lifting device above described will be readily understood. Assuming that it has a mass of 30 coal piled on the ground or on the floor surface which is to be removed or loaded into the wagon or car, the mechanism is first moved into suitable position. If it is to be transported a considerable distance the 35 weight of the apparatus is thrown as much as possible upon the two ground wheels B by lifting the front or shovel end by the lever 33. If it is desired to work toward the right the shovel plate (12) is brought 40 near the bottom of the pile on its left side. The hook or attaching device (35') is then secured to a post or anchor some distance to the right. The motor or engine is then started and this puts the endless conveyer in 45 action. An operative by means of the crank at (37') causes the winding up of the cable or chain (35). This causes the shovel plate to move under or into the mass of material which as soon as it falls or slips upon the 50 plate (12) is caught by the traveling flights (21) which sweep it over the plate (12) then carry it up the inclined guideway until it reaches the chute (39), which is arranged to guide it into the vehicle that is to receive it. 55 If it is desired to attack the pile of material from the right side, the machine is suitably placed and the feeding device (35) with its hook is fastened to a suitable anchor on the left. If at any time severe obstructions 60 are met the shovel plate can be moved by means of the lever until it is free to again be drawn forward.

If it is desirable to thrust the shoveling apparatus directly forward after it has been 65 put in proper initial position, the draft de-

vice (35) and its fastener are carried forward to an anchor which is directly in front of the machine and then the action of the winder will be to cause its gradual advance forward.

I am aware that numerous mechanisms have been proposed, each comprising a wheel supporting frame, a traveling platform and inclined conveying apparatus. Most of these mechanisms that have been made or proposed 75 have been designed and adapted for use on tracks, which latter fix the lines of travel of the wheels. Mechanisms of this class are not adapted for use in coal yards or places where the expense and labor incident to the 80 laying or changing of tracks is prohibitive. The mechanism herein presented can be readily and quickly taken from one point to another in any direction, either to the right or the left, or forward or backward.

Again, in the mechanisms heretofore proposed, the shovel mechanism has been united by hinges, or flexibly, to the main frame or to the elevator frame, and in most cases the elevator frame has been joined by vertical 90 pivot connections to the main frame.

I provide a true shovel which is rigid with the main frame or wheel frame and which, no matter in what position it may be put, has the same radial relationships to the 95 wheel axis. The shovel proper can be thrust directly laterally or forward into the material and is operable in any direction except backward. This shovel part is in the lowermost plane and can therefore be caused to 100 clean up the ground or floor surface. It furnishes the third ground support for the system. The parts are so arranged as to have an approximate counterbalance in relation to the main wheels, which largely assist in 105 carrying it or adjusting it in relation to the work to be done.

What I claim is:

1. A trackless portable shoveling and loading apparatus having in combination a horizontally arranged shovel plate adapted to be thrust horizontally under or into the material to be loaded, two ground wheels having their ground contacting points substantially in the plane of the shovel plate, a main frame mounted upon said wheels and rigidly connected to the shovel plate whereby the latter can oscillate bodily around the axis of the wheels, while held in fixed positions relatively thereto, power devices mounted on the 110 frame and adapted to swing the wheels laterally and move the shovel in either direction sidewise under the material to be loaded, a backward extending supporting frame along which the material is carried from the 115 shovel, and an endless carrier adapted to engage with the material on the shovel and carry it therefrom up the said inclined frame and deliver it, substantially as set forth.

2. A trackless portable shoveling and 120

loading apparatus having in combination, a horizontally arranged shovel plate adapted to be thrust laterally under or into the material to be loaded, two ground wheels 5 having their main contacting points substantially in the plane of the shovel plate, a main frame mounted upon said wheels, and rigidly connected to the shovel plate whereby the latter can oscillate bodily 10 around the axis of the wheels while held in fixed positions relatively thereto, means for applying power to cause the said wheels to swing or oscillate horizontally while carrying the shovel plate rigidly therewith, an 15 upward and backward inclined frame rigidly secured to the shovel plate and swinging laterally with the wheels, conveying mechanism mounted on the said inclined frame and shovel and arranged to 20 carry the material from the shovel along the said inclined frame, and power devices for actuating the said conveying mechanism mounted upon the framework supporting the aforesaid parts and held fixed in relation 25 to the parts actuated thereby while they are, as an entirety, moving around a vertical axis at or near the said wheels, substantially as set forth.

3. A portable shoveling and loading apparatus having in combination a main frame, supporting wheels therefor, an inclined frame extending from points in front to points in rear of said wheels and above them, a shovel plate rigidly secured to the 35 inclined frame and constructed substantially as set forth and having extended shoveling edges on lines intersecting the vertical plane of the wheel axis and with attaching devices, whereby it is adapted 40 to have a manual lever-like device applied directly thereto for moving laterally the wheels, the shovel plate and the inclined frame to carry load to the shovel plate, and a conveyer apparatus mounted on the inclined frame and shovel plate, substantially 45 as set forth.

4. A portable shoveling and loading apparatus having in combination a main frame, two supporting wheels carrying it, 50 an inclined frame extending from points in front to points in rear of said wheels on lines above them, a shoveling plate secured rigidly to the inclined frame and having longitudinally arranged shoveling edges, a 55 conveying apparatus adapted to remove from the shoveling plate the material received over the said shoveling edges and to then transport it upward on the said inclined frame, power mechanism on, and 60 maintained rigidly in relation to, the main and inclined frames, and a power transmitter connected to said mechanism for swinging the wheels, the shovel and the frames laterally in either direction, substantially 65 as set forth.

5. A trackless portable shoveling and loading apparatus, having in combination a main frame, two transversely opposite ground wheels on the main frame adapted to move in any direction over the ground, 70 a horizontal shovel plate rigidly mounted in relation to the main frame and having lateral shoveling edges on longitudinal lines, an upwardly inclined frame connected rigidly to the main frame, the said frames, 75 the shovel plate and the axis of said wheels being held in fixed relative positions and the entirety adapted to swing bodily horizontally with the said wheels, an endless continuously traveling conveying mechanism adapted to remove the material from the shovel plate and carry it up the inclined frame and deliver it in the rear of the wheels, a power mechanism on the framework for driving said conveying 80 mechanism, and a power transmitter on the frame adapted to cause the lateral motion of the aforesaid shovel plate, the ground wheels and the frame.

6. A trackless portable shoveling and loading apparatus having in combination, a main frame, two axially aligned truck wheels on said frame, an inclined frame rigid with the main frame and vibrating therewith about the axis of said wheels, a 90 shovel plate rigidly secured to the lower end of the inclined frame and extended forward and laterally in horizontal planes, and formed with shoveling edges on horizontal lines of the machine and adapted to 95 slide over the surface of the ground and provide a third point of ground support for the frame, an endless conveyer arranged to travel over the upper surface of the horizontal shovel plate and also on the 100 upward inclined frame, a motor on said frame for driving said conveyer, said parts being arranged substantially as set forth whereby they will all be held in fixed relative positions while the machine is moving 105 laterally and in operation.

7. A trackless, portable and shoveling apparatus having in combination a main frame, two axially aligned truck wheels mounted on the main frame, an inclined 115 frame rigid with the main frame, a flat horizontal traveling plate rigidly secured to the lower end of the inclined frame and adapted to provide a third point of ground support for the main frame at points in 120 front of the wheels and to slide on the surface of the ground under the material to be loaded, the said parts being arranged as described to permit the entire structure to be supported on said two wheels alone or 125 on said wheels and the said plate and also to be swung laterally on the ground contacting points of the wheels, a single endless conveyer traveling in two planes at an angle to each other and adapted to en- 130

gage with the material on the shovel plate while traveling in one of the said planes and carry it therefrom to and up the inclined frame while traveling in the other plane, 5 and power devices for driving the said conveyor mounted stationarily relatively to the ground wheels, substantially as set forth.

In testimony whereof I affix my signature, in presence of two witnesses.
